UNITED STATES PATENT OFFICE.

TAKANOSHIN DOMOTO, OF OAKLAND, CALIFORNIA.

DESIGN FOR A VASE.

Application filed September 13, 1922. Serial No. 3,710. Term of patent 7 years.

To all whom it may concern:

Be it known that I, TAKANOSHIN DOMOTO, a subject of the Emperor of Japan, residing at Oakland, county of Alameda, and State of California, have invented a new, original, and ornamental Design for Vases, of which the following is a specification, reference being had to the accompanying drawing, forming part thereof.

Fig. 1 is a side view of a vase showing my design.

Fig. 2 is a central vertical section of a vase showing my design.

Fig. 3 is a top view of a vase showing my design.

I claim:

The ornamental design for a vase, as shown.

TAKANOSHIN DOMOTO.
